UNITED STATES PATENT OFFICE.

CHARLES L. NEDOMA, OF DETROIT, MICHIGAN, ASSIGNOR OF ONE-HALF TO FRANK M. HAWLEY, OF DETROIT, MICHIGAN.

CARBURETER.

1,190,573.

Specification of Letters Patent. Patented July 11, 1916.

Application filed June 26, 1915. Serial No. 36,465.

To all whom it may concern:

Be it known that I, CHARLES L. NEDOMA, a subject of the Emperor of Austria-Hungary, residing at Detroit, in the county of 5 Wayne and State of Michigan, have invented a new and useful Carbureter, of which the following is a specification.

The present invention consists in a carbureter, among the important features of 10 which are the following: a series of fuel orifices located in the wall of the mixing chamber, together with a movable tubular fuel valve for opening and closing the orifices; means for simultaneously imparting movement to the tubular valve and to the throttle valve; means whereby the movement of the tubular valve, in respect to regulating the supply of fuel, is rendered effective in accordance with the demands of the engine 15 at different stages of throttle opening; cam means for regulating the movement of the tubular valve; and a throttle valve, including a secondary air valve, whereby air alone may be admitted to the engine for braking 20 and cooling purposes.

The invention also consists in the details of construction shown, described and particularly pointed out in the subjoined claims.

In the drawings, Figure 1 is a side elevation, parts being broken away, showing one embodiment of my invention. Fig. 2 is a section on the line 2--2 of Fig. 1, the cam mechanism appearing in elevation and the throttle being (as in Fig. 1) in position to 30 admit air only for braking or cooling purposes. Fig. 3 is an enlarged fragmentary section of the cam and cam carrier. Fig. 4 is a vertical section through a modification. Fig. 5 is a plan view of the jet-plate. Fig. 40 6 is a plan view of the fuel valve shown in Fig. 4. Fig. 7 is a fragmentary vertical section through the lower portion of the same fuel valve. Fig. 8 is a vertical section 45 through a second modification. Fig. 9 is a vertical section through a third modification. Fig. 10 is a fragmentary section on the line 10--10 of Fig. 8.

Similar reference characters refer to like parts throughout the several views.

50 In the embodiment of my invention shown in Figs. 1, 2 and 3, 1 indicates an ordinary

float chamber, the supply of fuel for which is controlled by the float 2 in the usual way. Formed integrally with the float chamber is the carbureting chamber casing 3 which 55 may be flanged at 4 for attachment to the engine manifold and has its lower end of increased diameter, as indicated at 5. The interior of the lower end is provided with the face 6 having an annular fuel duct 8 formed therein to which fuel from the float chamber flows through the passage 9; and adjacent the face 6 the wall is threaded to receive the ring 10 by which the annular jet plate 11 (Fig. 5), preferably of thin copper, is clamped in position. The jet plate is provided in its inner edge with a series of spaced notches 12, that may be V-shaped and have their pointed ends in communication with the duct 8 while their opposite 60 ends open into the carbureting chamber. As shown, the ring 10 and casing 3 are cut to form a frusto-conical valve seat 13 above which the inner surface of the carbureting chamber is shaped to receive the body portion 75 14 of an axially rotatable tubular fuel valve, the upper edge of which may engage the shoulder 15. From the lower edge of the body portion, the valve flares outwardly to form a lower end 16 having notches 18 80 corresponding in number and angular spacing to the notches 12 in the jet plate. The wall of the mixing chamber is provided with the circumferential slot 20 (Fig. 1), through which a pin 21, rigid with the fuel valve, 85 projects, and a spring 22, anchored at 23, tends to force the pin to the right end of the slot, in which position the fuel orifices are closed by the valve.

Mounted in ears 25 (but one of which is 90 shown) on the casing 3 is a transversely extending throttle shaft 26 to which is secured an arm 28 having its end slotted at 29 for a purpose hereinafter indicated, and this arm may have formed integral therewith an actuating lever 30. The shaft 26 also has secured thereto at a point in alinement with the axis of the carbureting chamber, a throttle arm 33 (Fig. 2), preferably a duplicate of the arm 28, that projects into the chamber through a narrow slot in an obvious manner. The arm 33 receives a cross pin 95 100

34 upon which a throttle rod 35 is suspended, said rod having its lower end guided in a boss 36 on a laterally opening intake member 38 secured to the casing 3 in 5 any desired manner. Upon the throttle rod is rigidly secured a substantially conical member or pure air valve 40 having its lower edge 41 conforming to a seat 42 on another member with respect to which the rod is capable of relative movement and the last 10 mentioned member is normally held in engagement with the member 40 by a compression spring 43, one end of which abuts a collar 44 on the rod. The member with respect to which the rod is movable is made 15 up of the cross wall 45 and an upwardly tapering conical portion 48 with which the cross wall merges, and is perforated at 49 from which it will be seen that the space between the cross wall 45 and the member 40 20 is constantly in communication with the atmosphere. The members 40 and 45-48 together constitute a throttle valve; and, when the parts are in the position indicated in 25 Fig. 2, air is admitted to the mixing chamber through the perforations 49 without any flow of fuel from the notches 12.

The means for rotating the fuel valve about the axis of the mixing chamber will 30 now be described:—Suspended from a pin 50 that passes through the slot 29 in the arm 28 is a cam carrier support 51 having its lower end slotted at 52 to inclose a headed screw 53 that projects from the casing, and 35 having its upper end 54 guided in a perforated lug 55 on the casing. The support 51 includes two guides 56 and a connecting plate 58 which may be detachably secured thereto by screws 59; and slidable in the 40 guides is a cam carrier 60 that may be adjusted toward and from the pin 21 by means of the screw 61, threaded in the yoke 62, the ends of which pass through the plate 58 and the cam carrier 60 and are riveted on 45 the opposite side of the latter. Screws 64, that may be accessible with a driver through the holes 65 in the plate 58, or which may have heads 66, extend through the cam carrier and are rigidly secured to a flexible 50 cam 67, preferably formed of a strip of thin metal, that engages the pin 21 on the fuel valve. Since the screws may be independently adjusted, it follows that the cam 55 may be given any desired contour.

When the throttle is closed, the member 45-48 fits into the flaring lower end of the fuel valve and the member 40 is held in engagement therewith by the spring 43. At 60 this time, the notches 18 are maintained out of alignment with the notches 12 by the action of the spring 22; consequently, neither fuel nor air is admitted to the mixing chamber. The throttle being opened and the cam 66 being properly adjusted, for example, as shown in Fig. 3, the simultaneous

vertical movement of the cam carrier support causes the pin 21 and fuel valve to turn about a vertical axis, whereby the notches 18 gradually pass into registration with the notches 12, the amount of flow being determined by the width of registration. Thus the free passage may be increased rapidly at starting to insure a rich mixture, 70 may then increase gradually in accordance with the demands of the engine at intermediate speeds, and may afterward flatten out to reduce the richness of the mixture at the higher speeds to that consistent with economy, a wide range of adjustment being provided for. The curvature necessary to cause 75 the required relative opening of the fuel orifices throughout the various stages of speed having been imparted to the cam 67 by the screws 64, the screw 61 affords means whereby the cam may be moved bodily toward or from the pin 21 to vary the amount of fuel delivered without disturbing the rate in which it is fed at one time with respect to the rate of delivery at any other period. This, therefore, constitutes a convenient 80 means for securing a quantitative fuel adjustment suitable to conditions of weather or altitude. And not only is a proper supply of fuel secured as concerns quantity, but the fuel is applied to a thin sheet of air in 85 such manner in all instances as to allow a maximum atomizing action to take place.

The engine may be used as a brake on motor vehicles while coasting or may be cooled by simply thrusting the throttle lever 100 (from initial or closed position) in a direction opposite to that in which it is moved for opening purposes, whereupon the secondary valve 40 assumes the relation to the member 45-48 indicated in Fig. 2, and air 105 only is admitted to the mixing chamber.

The embodiment shown in Fig. 4 differs from that previously described mainly in the arrangement of the float chamber and in the reversal of the throttle and fuel valves, 110 with consequent reversal in the flow of air. The fuel reservoir 70 in this instance is formed integrally with and surrounds the carbureting chamber casing 71, and the annular float 72 controls the lever of liquid. 115 The upper end of the casing is faced at 73 and provided with the annular fuel duct 74, to which liquid passes through the passage 75. Threaded on the upper end of the casing 71 is the intake member 76, to which air 120 is admitted through a pipe 78 that may lead to any desired source of warm air as, for example, a point adjacent the exhaust manifold. A plate 11 clamped between the face 73 and the member 76 performs the same 125 function as the plate 11 shown in Fig. 1.

The casing 71 and the member 76 are shaped to form a valve seat 78 upon which rests the tapering lower end 79 of a fuel valve, the tubular body portion 81 of which 130

is provided with slots 82 for the admission of air from an annular passage 83 in the member 76; while a throttle valve, consisting of the members 85 and 86 that correspond in operation and differ but slightly in structure, respectively, from the members 40, 45—48, controls the flow of air. The throttle rod 88, guided in a spider 89 on the member 71 and in the plug 90 threaded into the upper end of the intake member, is surrounded by a spring 92 that tends to hold the throttle valve upon its seat. As shown, the upper end of the rod has secured thereto a grooved collar 91 into which is received the yoked end 92' of an arm 93 rigid with the throttle shaft 94.

It will be understood that a movement of the throttle shaft for the purpose of opening or closing the throttle valve imparts a simultaneous movement to the fuel valve, and for this purpose a cam and cam actuating means such as shown in Figs. 1 and 2 is provided (not shown, since these elements are on the side of the carburetor between the eye and the section plane in Fig. 4). The operation of the device is substantially the same as that of the form previously described.

The modifications illustrated in Figs. 8 and 9 differ from that shown in Fig. 4 primarily in that the fuel valve moves vertically rather than angularly.

Referring to Fig. 8, the mixing chamber casing 100 has its lower end of increased diameter to receive the duct plate 101 (in which is formed the annular fuel duct 102 which receives its fuel through the passage 103 from any suitable source), the jet plate 11, the annular clamping plate 104 and the threaded intake member 105. The latter is shaped to form a valve seat 106, and has a valve guide 108 threaded into its lower end, through which the rod 109 carrying the tapering valve 110 is vertically slidable. Upon its lower end the rod rests upon an arm 112 secured to a connecting rod 113 that passes through a lug 114 on the casing 100 and has its upper end offset at 113' to align with a throttle lever 114' to which it is connected by the pin-and-slot 115'. The throttle lever is pivotally supported on the casing at 116 and has a lug or short arm 118 that engages with one end of a lever 119 pivoted to the casing at 120; the opposite end of the lever 119 supports the tubular fuel valve 120' and imparts movement thereto through the pin 121 and slot 122, the fuel valve being normally held in position to close the fuel orifices by a spring 123 secured to the pin 121 and anchored to the casing at 124. As the throttle lever is thrown counterclockwise to depress the throttle valve, the pin 121 and valve 120' are elevated to open the fuel orifices; and in order to secure a progressive increase in the total free fuel opening, the lower edge of the valve 120 is provided with a series of notches

124' (one for each notch 12 in the orifice plate) of different depths whereby the fuel orifices are opened one after another. By properly locating the notches, the range of mixtures may be varied to suit the demands of the engine under a wide range of conditions.

In Fig. 9, as in Fig. 4, the direction of flow of air is downward and the fuel reservoir 125 is formed with and surrounds the mixing chamber casing 126. The latter is, however, extended downward and laterally at 128 and provided with an ordinary butterfly valve 129, the shaft 130 of which is secured to the operating lever 131. Slidably vertically in the intake member 132 is a tubular valve 133, the counterpart of valve 120, from which a pin 134 projects through a slot 135 and a link 136 that is pivoted at 137 to the lever 131. A spring 138 attached to the pin 134 and anchored to the casing at 139 tends to hold the valve 133 in the position shown. The fuel passage 140, annular duct 141, jet-plate 142 and clamping plate 143 are the same as previously described; and the operation of the foregoing elements is substantially the same as that of the modification shown in Fig. 8, except as concerns the reverse flow of the air. Threaded into the end of the intake member is a spider 143 that, together with the threaded spider 144 on the casing 126, constitutes a guide for the air current controlling cone 145, adjustment of which is secured by manipulating the finger piece 146 in an obvious manner.

It is clear that many changes may be made in the details of construction without departing from the spirit of my invention; for example, the notches or passages for the fuel from the annular duct to the mixing chamber may be cut either in the wall of the mixing chamber casing or in the wall of the intake chamber. I do not, therefore, wish to be limited otherwise than as indicated by the subjoined claims.

I claim:—

1. A carburetor comprising in combination a tubular casing forming an air passage, said casing including a fuel passage leading inwardly through the wall thereof, a tubular fuel valve conforming to a portion of the wall of the air passage, a throttle valve for controlling the flow of air through the air passage, and means for simultaneously operating the fuel valve and the air valve, said fuel valve being movable in one direction in respect to the casing and said throttle valve being movable in another direction.

2. A carburetor comprising in combination a tubular casing forming an air passage, said casing including a fuel passage leading inwardly through the wall thereof, a tubular fuel valve conforming to a portion of the wall of the air passage, and a throttle

valve for controlling the flow of air through the air passage, means for moving said fuel valve in one direction in respect to the casting, and means for moving said throttle valve in another direction.

3. A carburetor comprising in combination a tubular casing forming an air passage, said casing including two sections, one an intake section and the other a casing for a carbureting chamber, and a ring-like jet plate located between the sections, said jet plate having a series of notches in its inner edge, said notches extending through the jet plate in a direction parallel to the axis thereof, means for supplying fuel to the notches, and a tubular fuel valve conforming to the interior of a portion of the air passage casting for regulating the flow of fuel from the notches.

20. 4. A carburetor comprising in combination a tubular casing forming an air passage, said casing including two sections, one an intake section and the other a casing for a carbureting chamber, and a thin annular jet plate located between the sections, said jet plate having a series of notches in its inner edges, said notches extending through the jet plate in a direction parallel to the axis thereof, means for supplying fuel to the notches, and a tubular fuel valve conforming to the interior of a portion of the air passage casting for regulating the flow of fuel from the notches.

5. A carburetor comprising in combination a tubular casing forming an air passage, said casing including two members, and a thin annular jet plate located between the members, said jet plate having a series of notches in its inner edge, said notches extending through the jet plate in a direction parallel to the axis thereof, means for supplying fuel to the notches, a hollow tubular air valve conforming to the air passage at a point adjacent the jet plate, and means for moving the fuel valve in reference to the notches for regulating the flow of fuel.

6. A carburetor comprising in combination a tubular casing forming an air passage, said casing including two portions, one an intake section and the other a casing for a carbureting chamber, and a thin annular jet plate located between the sections, said jet plate having a series of notches in its inner edge, said notches extending through the jet plate in a direction parallel to the axis thereof, means for supplying fuel to the notches, the air passage adjacent the jet plate being cylindrical in cross-section, a hollow cylindrical fuel valve conforming to the cylindrical portion of the air passage, and means for moving the fuel valve angularly about its axis for regulating the flow of fuel from the notches.

60. 7. A carburetor comprising in combination

a tubular casting forming an air passage, said casting including two sections, one an intake section and the other a casting for a carbureting chamber, and a thin annular jet plate located between the sections, said jet plate having a series of notches in its inner edge, means for supplying fuel to the notches, the air passage adjacent the jet plate being cylindrical in cross-section, a hollow cylindrical fuel valve conforming to the cylindrical portion of the air passage, a throttle valve for the air passage, a fuel valve for admitting fuel angularly about its axis for regulating the flow of fuel from the notches, and means for moving the fuel valve to control the flow of fuel.

8. A carburetor comprising in combination a tubular casting forming an air passage, said casting including a series of fuel passages leading inwardly through the wall thereof, means for supplying fuel to the passages, a tubular fuel valve conforming to the wall of the air passage and being arranged to close the fuel passages when in one position, means for moving the fuel valve, a throttle valve for controlling the flow of air through the air passage, said throttle valve including a plurality of members, means for imparting angular movement to the throttle valve as a solid and to the fuel valve, the arrangement being such that when the throttle valve is moved in one direction from initial position both fuel and air are admitted to the air passage, and when a portion of the throttle valve is moved in the opposite direction air only is admitted.

9. A carburetor comprising in combination a tubular casting forming an air passage, said casting including a series of fuel passages leading inwardly through the wall thereof, a fuel valve for controlling the flow of fuel through the fuel passages, a throttle rod, a throttle valve comprising a plurality of members carried by the rod, said members being arranged to form a seal with respect to the air passage, or to allow the flow of air only, or to allow the flow of both air and fuel, resilient means tending to hold the members in the first named relation, and means for applying force to the throttle rod to cause the members to assume either of the last named relations at will.

10. A carburetor comprising in combination a tubular casting forming an air passage, said casting including a series of fuel passages leading inwardly through the wall thereof, a fuel valve for controlling the flow of fuel through the fuel passages, a throttle rod, a throttle valve comprising a plurality of members carried by the rod, said members being arranged to form a seal with respect to the air passage, or to allow the flow of both air and fuel, resilient means tending to hold the members in the first named relation, and means for applying force to the throttle rod to cause the members to assume either of the last named relations at will.

- of air only, or to allow the flow of both air and fuel, resilient means tending to hold the members in the first named relation, means for applying force to the throttle 5 rod to cause the members to assume either of the last named relations at will, and means for connecting the force-applying means to the fuel valve whereby when the throttle valve is in the position to allow 10 the flow of both fuel and air, the fuel valve is in position also to allow the flow of fuel.
11. A carbureter comprising in combination a tubular casing forming an air passage, said casing including a series of fuel 15 passages leading inwardly through the wall thereof, a tubular fuel valve conforming to the wall of the air passage, said valve having a frusto-conical end arranged to control the flow of fuel, a throttle rod movable longitudinally of the air passage, a throttle valve carried by the rod, said valve including two members one fixed to the rod and one movable in respect thereto, one of the members including a valve seat and the 20 other constituting a pure air valve adapted to engage the seat, resilient means for normally holding the secondary valve in engagement with the seat, means for moving the rod with the throttle valve members 25 in the direction away from the frusto-conical end of the throttle valve and for simultaneously moving the fuel valve to open the fuel passages, whereby both fuel and air are admitted to the air passage, said means 30 also being adapted to move the secondary valve in the opposite direction away from the frusto-conical end of the fuel valve, whereby air only is admitted to the air passage.
12. A carbureter comprising in combination a tubular casing forming an air passage, a throttle valve for the air passage, a fuel jet leading to the air passage, a tubular 5 valve conforming to the wall of the air passage for regulating the flow of fuel from the jet, means for simultaneously moving the throttle valve and the fuel valve to admit air and fuel to the air passage, cam 10 means for controlling the movement of one of the valves with reference to the other.
13. A carbureter comprising in combination a tubular casing forming an air passage, a throttle valve for the air passage, a fuel jet leading to the air passage, a tubular 15 valve conforming to the wall of the air passage for regulating the flow of fuel from the jet, means for simultaneously moving the throttle valve and the fuel valve to admit air and fuel to the air passage, cam 20 means for controlling the movement of one of the valves with reference to the other, said cam means being adjustable to cause a different ratio of movement of the valves at one stage of operation than at another.
14. A carbureter comprising in combination a tubular casing forming an air passage, a throttle valve for the air passage, a fuel jet leading to the air passage, a tubular 25 valve conforming to the wall of the air passage for regulating the flow of fuel from the jet, means for simultaneously moving the throttle valve and the fuel valve to admit air and fuel to the air passage, cam means for controlling the movement of one of the valves with reference to the other, said cam means being adjustable to cause a different ratio of movement of the valves at one stage of operation than at another, and additional means for adjusting the cam means without disturbing the first mentioned adjustment.
15. A carbureter comprising in combination a tubular casing forming an air passage, a throttle valve for the air passage, a fuel jet leading to the air passage, a hollow cylindrical fuel valve conforming to the wall of the air passage, means for moving the throttle valve to admit air to the air passage and for simultaneously turning the cylindrical fuel valve about its own axis to admit fuel, said last mentioned means including a cam for regulating the rate of movement of the fuel valve with reference to the rate of movement of the throttle valve.
16. A carbureter comprising in combination a tubular casing forming an air passage, a throttle valve for the air passage, a fuel jet leading to the air passage, a hollow cylindrical fuel valve conforming to the wall of the air passage, means for moving the throttle valve to admit air to the air passage and for simultaneously turning the cylindrical fuel valve about its own axis to admit fuel, said last mentioned means including a cam for regulating the rate of movement of the fuel valve with reference to the rate of movement of the throttle valve, and means for adjusting the cam to vary the ratio of the movements of the valves at different stages of throttle valve opening.
17. A carbureter comprising in combination a tubular casing forming an air passage, a throttle valve for the air passage, a fuel jet leading to the air passage, a hollow cylindrical fuel valve conforming to the wall of the air passage, means for moving the throttle valve to admit air to the air passage and for simultaneously turning the cylindrical fuel valve about its own axis to admit fuel, said last mentioned means including a cam for regulating the rate of movement of the fuel valve with reference to the rate of movement of the throttle valve, means for adjusting the cam to vary the ratio of the movements of the valves at different stages of throttle valve opening, and additional means for adjusting the cam means without disturbing the first mentioned adjustment.

- justment whereby the richness of the fuel mixture may be varied to correspond to weather or altitude.
18. A carburetor comprising means for forming an air passage, means for forming a fuel passage that leads to the air passage, a throttle valve for controlling the flow of air through the air passage, a fuel valve for controlling the supply of fuel, means for simultaneously moving the throttle valve and the fuel valve, said means for regulating the ratio of the movements of the valves to each other at different stages of throttle opening, and additional means for adjusting the cam means without disturbing the first mentioned adjustment whereby the richness of the fuel mixture may be varied to correspond to weather or altitude.
19. A carburetor comprising a casing forming an air passage including a cylindrical portion, means for forming a fuel passage that leads to the air passage, a throttle valve for controlling the flow of air through the air passage, a fuel valve for controlling the supply of fuel, one of the valves being movable longitudinally of the air passage and the other rotatable axially in respect to the cylindrical portion thereof, means, movable longitudinally in respect to the air passage, for simultaneously imparting movement to the valves, said means including a member movable longitudinally of the casing, a pin secured to the rotatable valve and projecting through a slot in the casing, resilient means tending to urge the pin toward one end of the slot, a flexible cam supported by the last-mentioned longitudinally movable member and contacting with the pin, said cam extending longitudinally of the casing, and means for varying the contour of the cam.
20. A carburetor comprising a casing forming an air passage including a cylindrical portion, means for forming a fuel passage that leads to the air passage, a throttle valve for controlling the flow of air through the air passage, a fuel valve for controlling the supply of fuel, one of the valves being movable longitudinally of the air passage and the other rotatable axially in respect to the cylindrical portion thereof, means, movable longitudinally in respect to the air passage, for simultaneously imparting movement to the valves, said means including a member movable longitudinally of the casing, a pin secured to the rotatable valve and projecting through a slot in the casing, resilient means tending to urge the pin toward one end of the slot, a flexible cam supported by the last-mentioned longitudinally movable member and contacting with the pin, said cam extending longitudinally of the casing, and means for varying the contour of the cam.
21. A carburetor comprising a casing forming an air passage including a cylindrical portion, means for forming a fuel passage that leads to the air passage, a throttle valve for controlling the flow of air through the air passage, a fuel valve for controlling the supply of fuel, one of the valves being movable longitudinally of the air passage and the other rotatable axially in respect to the cylindrical portion thereof, means, movable longitudinally in respect to the air passage, for simultaneously imparting movement to the valves, said means including a member movable longitudinally of the casing, a pin secured to the rotatable valve and projecting through a slot in the casing, resilient means tending to urge the pin toward one end of the slot, a cam carrier supported by the last mentioned longitudinally movable member, said cam carrier being movable transversely of the casing, means for moving the cam carrier transversely of the casing, a flexible cam supported on the cam carrier, and means for varying the contour of the cam.
22. A carburetor comprising a casing forming an air passage including a cylindrical portion, means for forming a fuel passage that leads to the air passage, a throttle valve for controlling the flow of air through the air passage, a fuel valve for controlling the supply of fuel, one of the valves being movable longitudinally of the air passage and the other rotatable axially in respect to the cylindrical portion thereof, means, movable longitudinally in respect to the air passage, for simultaneously imparting movement to the valves, said means including a member movable longitudinally of the casing, a pin secured to the rotatable valve and projecting through a slot in the casing, resilient means tending to urge the pin toward one end of the slot, a cam carrier supported by the last mentioned longitudinally movable member, said cam carrier being movable transversely of the casing, a flexible cam supported on the cam carrier, and means for varying the contour of the cam.
23. A carburetor comprising in combination a tubular casing forming an air passage, said casing including a series of spaced fuel passages leading inwardly through the wall thereof, means for supplying fuel to the passages, a tubular fuel valve conforming to the wall of the air passage, means for moving the fuel valve, said fuel valve having a series of fuel passages corresponding to the fuel passages in the casing, the arrangement being such that the fuel passages in the fuel valve are progressively brought into registration with the passages in the casing.

24. A carbureter comprising in combination a tubular casing forming an air passage, said casing including a series of spaced fuel passages leading inwardly through the wall thereof, means for supplying fuel to the passages, a tubular fuel valve conforming to the wall of the air passage, means for moving the fuel valve, said fuel valve having a series of notches in its end corresponding in number to the fuel passages in the casing, some of the notches being of greater depth than others whereby the fuel passages in the casing are progressively brought into free communication with the air passage. 65
- 15 25. A carbureter comprising in combination a tubular casing forming an air passage, said casing including a series of spaced fuel passages leading inwardly through the wall thereof, means for supplying fuel to the passages, a tubular fuel valve conforming to the wall of the air passage, a throttle valve for controlling the flow of air through the air passage, means for simultaneously moving the throttle valve and the fuel valve to admit air and fuel, and a member arranged centrally of the fuel passage, said member being of greater cross-section at one point than at another and being adjustable longitudinally of the air passage whereby the depth of the stream of air flowing past the ends of the fuel passages may be regulated. 70
- 35 26. A carbureter comprising in combination a tubular casing forming an air passage, said casing including a series of spaced fuel passages leading inwardly through the wall thereof, means for supplying fuel to the passages, a tubular fuel valve conforming to the wall of the air passage, a throttle valve for controlling the flow of air through the air passage, means for simultaneously moving the throttle valve and the fuel valve to admit air and fuel and a conical member arranged centrally of the fuel passage, said member being adjustable longitudinally of the air passage for regulating the velocity of the air current past the ends of the fuel passages. 75
- 50 27. A carbureter comprising a casing forming an air passage, means for supplying fuel to the passage, a fuel valve for controlling the rate of fuel supply, a throttle valve for controlling the flow of air through the air passage, said throttle valve including a plurality of members, means for imparting simultaneous movement to the throttle valve as a whole and to the fuel valve, the arrangement being such that when the throttle valve is moved in one direction from initial position both fuel and air are admitted to the air passage, and when a portion of the throttle valve is moved in the opposite direction air only is admitted. 80
- 55 28. A carbureter comprising a casing forming an air passage, means for supplying fuel to the passage, a fuel valve for controlling the rate of fuel supply, a throttle valve for controlling the flow of air through the air passage and comprising a plurality of members, throttle valve controlling means, a throttle valve comprising a plurality of members, said members being arranged to form a closed wall across the air passage, or to allow the flow of air only, or to allow the flow of both fuel and air, 85 resilient means tending to hold the members in the first named relation, and means for applying force to the throttle valve controlling means to cause the members to assume either of the last named relations at 80 will. 90
29. A carbureter comprising a casing forming an air passage, and a throttle valve for controlling the flow of air through the passage, a seat for the throttle valve, said throttle valve comprising a plurality of members arranged to form a closed wall across the opening, means for moving the members simultaneously in one direction to allow passage of air through the space between the valve and the seat, and for moving one of the members in the opposite direction and in respect to the remainder of the valve to allow passage of air between it and the rest of the valve. 95
30. A carbureter comprising in combination a tubular casing forming an air passage, a throttle valve for the air passage, a fuel jet leading to the air passage, a tubular valve conforming to the wall of the air passage for regulating the flow of fuel from the jet, means for simultaneously moving the throttle valve and the fuel valve to admit air and fuel to the air passage, and adjustable means for controlling the movement of one of the valves with reference to the other. 100
- 35 31. A carbureter comprising in combination a tubular casing forming an air passage, a throttle valve for the air passage, a fuel jet leading to the air passage, a tubular valve conforming to the wall of the air passage for regulating the flow of fuel from the jet, means for simultaneously moving the throttle valve and the fuel valve to admit air and fuel to the air passage, and means for controlling the movement of one of the valves with reference to the other, said means being adjustable to cause a different ratio of movement of the valves at one stage of operation than at another. 105
- 40 32. A carbureter comprising in combination a tubular casing forming an air passage, a throttle valve for the air passage, a fuel jet leading to the air passage, a tubular valve conforming to the wall of the air passage for regulating the flow of fuel from the jet, means for simultaneously mov- 110

ing the throttle valve and the fuel valve to admit air and fuel to the air passage, and means for controlling the movement of one of the valves with reference to the other, said controlling means being adjustable to cause a different ratio of movement of the valves at one stage of operation than at another, and additional means for adjusting

the controlling means without disturbing the first mentioned adjustment whereby the richness of the fuel mixture may be varied to correspond to weather or altitude.

In testimony whereof I have signed this specification.

CHARLES L. NEDOMA.
